UNITED STATES PATENT OFFICE

92,122

DESIGN FOR A DISPLAY REFRIGERATOR

Joseph J. Weiss, New York, N. Y., assignor to The Jacobs Bros. Co., Inc., Brooklyn, N. Y., a corporation of New York

Application January 17, 1934, Serial No. 50,430

Term of patent 3½ years

To all whom it may concern:

Be it known that I, JOSEPH J. WEISS, a citizen of the United States, residing at New York, in the county of Bronx and State of New York, have invented a new, original, and ornamental Design for Display Refrigerators, of which the following is a specification, reference being had to the accompanying drawing, forming part thereof,

I claim:

The ornamental design for a display refrigerator, as shown and described.

JOSEPH J. WEISS.
